UNITED STATES PATENT OFFICE.

DURWARD CUTHBERT COLLIER AND FLOYD MILLEDGE MURPHY, OF BARNESVILLE, GEORGIA, ASSIGNORS TO COLLIER MILLS, INC., OF BARNESVILLE, GEORGIA, A CORPORATION OF GEORGIA.

GARMENT.

1,404,273.

Specification of Letters Patent. Patented Jan. 24, 1922.

Application filed February 9, 1921. Serial No. 443,588.

To all whom it may concern:

Be it known that we, DURWARD C. COLLIER and FLOYD M. MURPHY, citizens of the United States, and residing at Barnesville, 5 Pike county, State of Georgia, have invented certain new and useful Improvements in Garments, of which the following is a specification.

This invention relates to knit underwear or union suits for the use of women, and has among its objects and advantages simplicity of construction contributing to the ease of manufacture and low cost of production, a saving of the material from which 10 they are made by avoiding waste scraps of the material by reason of the shape and manner of cutting from the original fabric the parts going to make up the garment, and greatly increased ease and comfort to the wearer, 15 due to the structural arrangement and connection of the parts making it specially adapted to the different conditions of use. The novel features will be apparent from the following description and claims taken 20 with the drawings.

In the drawings:

Figure 1 shows a tubular knitted fabric cut for the neck and arm openings and slit vertically and centrally for the legs.

30 Figure 2 shows the two main gussets to be inserted at the rear extending down the legs and the way of cutting them.

Figure 3 shows one of two identical smaller gussets or insertions for the front extending 35 down the leg.

Figure 4 is a front view of the garment completed, and

Figure 5 is a rear view of the garment.

The main body of the garment is made 40 from tubular knitted fabric which is cut across at proper points for the neck portion and the lower ends of the legs. As shown in Figure 1 the tube section when lying flat is cut inwardly from the margins on curved

45 lines to form arm holes 10 and 11 and between their upper inner edges the end material is cut away on a curve 12 of larger diameter to form the neck opening between, and as illustrated in Figure 4 a continuous 50 binding strip 13 is attached to the edges forming the arm holes and having a connecting portion between the upper inner edges of the arm holes forming a part of the shoulder straps 14. Another continuous 55 binding strip 15 is secured around the mar-

gin of the neck opening and extends upwardly at the arm openings with and secured to the strips 13 forming part of the shoulder straps 14. At its lower end the tubular section 16 is cut on the side which 60 forms the rear part of the garment on a longitudinal central line from the bottom to the point 17, and the opposite part which forms the front of the garment is cut on a similar line terminating at 18 the proper 65 distance below 17 and nearer the lower edge. This leaves the lower depending sections 19 and 20 which with the gussets or inserts to be described form the legs of the garment.

70 The two main gussets or inserts which in cooperation with parts 19 and 20 aid in forming the legs, are made as shown in Figure 2 by the use of a rectangular piece of textile fabric similar to that of the tubular 75 section 16 but of greater length than width cut diagonally or at an angle to the sides from the point 21 at one end to the point 22 at the other end. The point 21 is a distance from the side 24 equal to that of the 80

point 22 from the side 23, and thus there is produced two identical gussets 25 and 26 adapted for use in forming the legs with no loss of material or scrap waste. These gussets as will be seen in Figure 2 have the 85

straight sides 23 and 24 and the inclined sides 27 and 28 cut on the bias and somewhat longer than sides 23 and 24, the narrow transverse ends 29, 30, and the wider ends 31, 32. In forming the legs an additional 90 or supplemental gusset 33 of similar textile fabric shown in Figure 3 is used in each leg and since they are identical only one is shown in this figure. It has a longitudinal straight side 34 and on the other side is cut 95 to taper from the point 35 on one side to a sharp angular end or point 36, and on the other side to a short transverse end edge 37.

100 As shown in Figure 5 in assembling the parts the gusset 25 is placed on the main body of the garment with the upper end of the straight side 23 at the point 17 where the vertical slot in the fabric ends and the short end 29 is stitched to the outer face of the fabric transversely. The straight edge 23 is then connected to the free edge 38 of the garment (see Figure 1) from the point 17 to the lower end of the leg portion 19. The lower, wider inner part of gusset 25 is 110

then folded in under the part attached to edge 38 and its lower inner point, shown at 21 in Figure 2, is secured to the lower inner point of the edge 39, Figure 1, on the front 5 portion of the folded part or leg 19 as shown in dotted lines in Figure 4. This adds the width of the end 31 of gusset 25 to the lower edge of the leg part 19 in forming the final leg opening at the bottom and this 10 gives ample room. Since however this gusset tapers upwardly and becomes narrower it is necessary to provide other means to secure a leg opening of proper size above the lower end. For this purpose and to secure 15 another function later described, the gusset 33 is secured along its straight sides 34 to the front edge 39 of the leg portion 19 from the top 18 to a point 36 near the lower edge of the leg portion as shown in Figure 4, the 20 length of the edge 34 corresponding to that of the edge 39. The edge of 33 from its point 36 to the point 35 is secured to the edge 27 of gusset 25 from 36 near its lower tip end, Figure 4, thus closing the sides of and 25 completing the leg from its lower end to a point somewhat less than half way to the point 18. The upper straight end 37 of gusset 33 is secured to the edge 40 of the front fold of the leg section 20 from point 18 30 downwardly. The gusset 26 and the other gusset corresponding to 33 are applied in a similar way to the other leg of the garment and further description is unnecessary. It will be noted, however, that as shown in 35 dotted lines in Figure 5, the gusset 26 at its upper end 30 passes under gusset 25 and that from its straight edge corner it is secured to the body on the same line as the edge 29 but on the opposite side of the point 17 and to 40 the inner surface of the body and that the two gussets thus overlap normally closing the rear opening of the garment but having free margins from 17 to the point 35 permitting them to be pulled to the sides at the 45 rear. The gussets 33 also overlap in front, the upper end 37 of one being under the upper end of the other and being secured respectively to the edges 39 and 40 on opposite sides of point 18. They have free edges 50 from 18 to 35. The lower tapered portions of the inserted gussets 33 compensate for the upward taper of gussets 25 and 26 in making the upper portion of the legs of sufficient size to adapt the garment to fit and be comfortable on the wearer.

It will be observed that the few pieces of fabric used are such simple easily made forms as to contribute greatly to a saving of time and labor in making them and securing 60 them together while at the same time reducing the waste of material in the cutting to a minimum.

It will be observed that the gussets or inserts 33 shown in Fig. 3 have one straight 65 side of full length and that the other side

is formed by two cuts similarly inclined from the opposite ends to a point at the center and it will thus be clear that a series of these gussets may be cut from a straight sided strip having a width equal to that of the gusset at its widest point without a waste of material and that this is true of a strip which in width is any multiple of the width of the gusset. The only possible waste is the small tip end cut away at 37.

Notwithstanding the simplicity of the parts and their connection they make it easy to produce a garment proportioned and adapted for the greatest comfort of the wearer and one adapted for easy and satisfactory adjustment.

Having thus described my invention, what is claimed as new and desired to be secured by Letters Patent is:

1. A garment of the class described, comprising a body portion of tubular fabric severed on a central longitudinal line from the lower end upward for a fixed distance to form leg portions, two similar gussets having straight sides and ends, one of the 90 sides being at right angles to the ends and the other inclined, the narrow ends of said gussets being secured to the body fabric at the rear at opposite sides of the severed line at the top, one being secured to the inner 95 and the other to the outer face of the fabric whereby they overlap and their lower ends extending down the leg portions and secured along their inner margins to the rear margin of the leg portion on the opposite 100 side of the rear line of severance and a pair of supplemental gussets corresponding to each other in shape and each having a straight side but inclined portions on the opposite side coming to a point at one end, 105 the straight side being secured to the front edge of the leg portion and the other side of the tapered portion ending in a point being secured to the front edge of the first mentioned gusset at its lower portion and 110 said supplemental gussets being secured at their upper ends to the front edge of the leg portion opposite to that to which its straight side is secured whereby these gussets overlap.

2. A garment of the class described, comprising a body portion of tubular fabric severed on a central longitudinal line from the lower end upward for a fixed distance to form leg portions, the cut at the rear 120 extending to a considerably higher point than that at the front, two similar gussets having straight sides and ends, one of the sides being at right angles to the ends and the other inclined, the narrow ends of said 125 gussets being secured to the body fabric at the rear at opposite sides of the severed line at the top, one being secured to the inner and the other to the outer face of the fabric whereby they overlap and their lower ends 130

extending down to the lower end of the leg portions and secured along their inner margins to the rear margin of the leg portion on the opposite side of the rear line of severance and a pair of supplemental gussets corresponding to each other in shape and each having a straight side but inclined portions on the opposite side coming to a point at one end, the straight side being secured to the 5 front edge of the leg portion to its lower end and the other side of the tapered portion

ending in a point being secured to the front edge of the first mentioned gusset at its lower portion and said supplemental gussets being secured at their upper ends to the 15 front edge of the leg portion opposite to that to which its straight side is secured, whereby these gussets overlap.

In testimony whereof we affix our signatures.

DURWARD CUTHBERT COLLIER.
FLOYD MILLEDGE MURPHY.
